Harry W. Bourne.

ATTORNEY.

UNITED STATES PATENT OFFICE.

GEORGE C. LASARES, OF SPRINGFIELD, MASSACHUSETTS.

TOY TRAIN.

1,321,109.

Specification of Letters Patent. Patented Nov. 11, 1919.

Application filed December 27, 1918. Serial No. 268,460.

To all whom it may concern:

Be it known that I, GEORGE C. LASARES, a citizen of the United States of America, residing in the city of Springfield, county of 5 Hampden, and State of Massachusetts, have invented certain new and useful Improvements in Toy Trains, of which the following is a specification.

This invention relates to improvements in 10 toy trains and more particularly to structures that are designed to be readily separated and reassembled. Broadly, the invention comprises a plurality of blocks, preferably solid, that are designed to be temporarily secured together by means of a 15 rod passing through openings in the blocks that are in alinement with each other and means on the rod for securing the same in place. The general outline of the blocks being that of a toy railway car, engine, or 20 tender.

The object of the invention is to provide a device that will amuse and instruct children in taking apart and reassembling the 25 blocks. Such a structure increases the child's powers of observation in matters relating to railway trains or other objects.

It is a well known fact that children are very much interested in and observant of 30 moving trains.

Referring to the drawings:

Figure 1 is a side elevational view of a train, showing the blocks assembled;

Fig. 2 is a sectional view of a car through 35 the axis of the securing rod for holding the blocks together; and

Fig. 3 is a perspective showing the blocks tipped or rotated about the securing rod at an angle to each other.

40 Referring to the drawings in detail: 1, 2, 3, and 4 conventionally designate the engine, tender, baggage and passenger cars, respectively, the substantially vertical lines 5, 6, 7, 8 and 9 of Fig. 2 indicate the surfaces 45 where the blocks fit together. The outline, or picture of a car, tender or engine is first pasted onto a piece of wood, the workman cuts the block, usually by means of a bandsaw along the outline of the picture. He 50 then saws this block up into several blocks on the lines indicated, producing the several blocks or pieces 10, 11, 12, 13, 14 and 15. The number, of course, is immaterial. Before a block, representing in outline an engine, tender, baggage or passenger car is cut 55 into the smaller blocks a hole is drilled or

bored longitudinally therethrough for receiving the securing pin 16. This pin is formed with openings at its ends to receive the pins 17 and 18. 19 designates a coil 60 spring which encircles the rod 16 and is located between the pin 18 and the end of the block or section 15. It is of course obvious that a larger or smaller number of sections may be produced as desired, and 65 any irregularity in the manner of sawing the blocks may be followed. Each of the units of the train, as the engine 1, tender 2, baggage car 3, are cut up into smaller sections in the manner just described and secured together by axially or longitudinally arranged rods like the rod 16. Each block or unit of the train is provided with means for attaching the same together to form the 70 complete train as shown in Fig. 1. The connecting means is shown at 20 which consists of a pin passing through openings in the extensions 21 of each unit of the train. Each unit of the train is mounted on movable wheels or rollers, consisting of a shaft 80 22, on the outer ends of which are secured the wheels 23. The shafts are rotatably mounted in projections or extensions 24 of the blocks. The train, as a whole, may be drawn about the floor as readily understood. 85 By removing one of the securing pins 17 or 18 the rod 16 may be removed and the several blocks arranged without any order with relation to each other. The child is then required to reassemble them to make the train 90 shown in Fig. 1. The spring 19 serves the purpose of automatically retaining the blocks in place.

If desired the several blocks 10, 11, 12, 13, 14 and 15 of a unit may be tipped about the 95 rod 16 with relation to each other, as shown in Fig. 3, to represent the idea that the train has met with an accident. Although only one unit of the train has been described as being cut into blocks or small sections it is 100 to be understood that the engine, tender and baggage car of the toy train is divided in the same manner as the car shown in Figs. 2 and 3.

It is to be understood that the elastic 105 or yieldable means shown for securing the sections together is not limited to a toy train structure as the rod and spring thereon may be used for temporarily securing together other toy objects which are divided 110 into sections as for example blocks of wood that represent animals, birds, fishes,

2
What I claim is:

1. A toy train comprising blocks to represent the various parts, or units, of the train, each block being formed into a plurality of blocks, of irregular shape, means for retaining the blocks of each unit in place by means of a rod passing through all of the blocks of the unit, and the rod having means on its ends for automatically retaining the blocks in close contact with each other.
2. A block having the outline of a unit of a toy train and divided into separable sections, means for retaining the sections in place comprising a device that engages all of the sections and spring means on the device for forcing the sections of the block together.
3. A block having the outline of a unit of a train and divided into separable sections, means for retaining the sections in place comprising a device that engages all of the sections and spring means on the device for forcing the sections of the block together, said retaining means permitting the

sections to be individually moved with relation to each other.

4. A dissected toy train comprising a plurality of train units, each unit being divided into a plurality of sections, means for securing the sections together to permit the same to be moved laterally of the longitudinal axis of the train and automatically retained in positions that are angular with respect to each other and a horizontal plane, and means for connecting the units together, as described.

5. A block for a unit of a separable toy comprising a solid member, cut into sections, and having an opening extending through all of the sections, a rod in the opening to secure the sections together, a spring on the rod for automatically retaining the sections in engagement with each other, and for permitting the sections to be moved laterally of each other about the rod, as described.

GEORGE C. LASARES.
